United States Patent Office

Des. 177,663
Patented May 15, 1956

177,663

VEHICLE SEAT OF THE ADJUSTABLE TYPE

Orville S. Caesar, Barrington, Ill.

Application August 31, 1954, Serial No. 32,095

Term of patent 14 years

(Cl. D15—8)

Fig. 1.

Des. 177,663

PAGE 2

Fig. 2.

Fig. 1 is a perspective view, taken from a high left front position, of a vehicle seat of the adjustable type, embodying my new design;

Fig. 2 is a perspective view thereof, taken from a high left rear position; and

Fig. 3 is a side elevation thereof.

I claim:

The ornamental design for a vehicle seat of the adjustable type, substantially as shown.
